UNITED STATES PATENT OFFICE.

HAZEN ABBEY, OF JACKSON, MICHIGAN.

PACKAGE-TIE.

1,202,145.

Specification of Letters Patent. Patented Oct. 24, 1916.

Application filed March 20, 1915. Serial No. 15,792.

To all whom it may concern:

Be it known that I, HAZEN ABBEY, a citizen of the United States, residing at Jackson, in the county of Jackson and State of Michigan, have invented a new and useful 5 Package-Tie, of which the following is a specification.

This invention relates to a tie especially designed for use in holding together packages of letters, cards, and other articles of a like nature, one of the objects of the invention being to provide a tie of this character which is simple in construction, cheap to manufacture, and which can be quickly 10 placed in position without the necessity of forming a knot, it being possible to draw the tie taut and to fasten it without the formation of any slack.

A further object is to provide a tie so constructed as to insure positively against the cord slipping from position after it has once been secured.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed, can be made within the scope of what is claimed, without departing from the spirit of the invention.

In the accompanying drawings the preferred form of the invention has been shown.

In said drawings:—Figure 1 is a perspective view of a package having the present improvements combined therewith, the position of the parts during the first step of tightening the tie about the package being illustrated. Fig. 2 is a similar view showing the final step of fastening the cord so that it will not slip out of place. Fig. 3 is 45 a side elevation of a portion of the package, the package tie being shown in section and the cord being likewise shown partly in section and partly in elevation and in the position assumed by it upon the completion of 50 the tying operation. Fig. 4 is a detail view of the buckle.

Referring to the figures by characters of reference 1 designates a finger piece having an opening 2 in one end portion thereof, 55 while extending from the other end is a stem 3 disposed at an obtuse angle, this

stem having its free end secured within a button 4, a portion of the periphery of which lies in the plane occupied by the bottom face of the finger piece 1. This button 60 has its marginal portion rounded as shown particularly in Fig. 3, and a cord receiving crotch 5 is formed between the back face of the button and the lower portion of the stem 65 3. The button 4 can be made integral with the stem, although in the structure shown it is made of a separate piece, preferably fiber, fixedly mounted on the stem in any suitable manner.

A cord of any desired length is secured at 70 one end in the opening 2, this cord being indicated at 6.

In using the tie, the cord 6 is wrapped about the package C in the usual manner after which the finger piece 1 is pressed 75 against the top of the package, thus bringing the periphery of the button 4 in contact with the top of the package. The free end portion of the cord is then looped about the button so as to rest on the stem 3 close to 80 the button. By now pulling the cord, the same will slip over the stem 3 and that portion of the cord extending from the package will wedge between the package and the button so as thus to be pinched therebetween. 85 After the cord has been drawn sufficiently taut, the operator swings the free end portion thereof laterally so as to draw it between the button and that portion of the cord on which the button rests, thus completing 90 a loop around the stem and causing a portion of the cord to be clamped between the back face of the button and that portion of the cord extending between the button and the package, as shown in Fig. 3. The 95 formation of one loop such as described is sufficient to prevent the cord from loosening, inasmuch as the cord is clamped between the package and the button 4 at the point indicated at a in Fig. 3 and is also clamped upon 100 itself and between the button and the package at the point indicated at b in Fig. 3. If desired, two or more loops can be made about the stem 3, although as before stated 105 this is unnecessary for the reason that after one loop has been completed as shown in Figs. 2 and 3, the cord will be held positively against slipping. By mounting the button 4 on an inclined stem 3, the upper portion of the button 4, which is inclined 110 away from the direction in which the cord is pulled by the operator, forms a hook so

that as the cord is pulled, it rides into the angle formed by the button and the upper portion of stem 3, the periphery of the button serving to deflect the cord to position between the button and the package. Thus, as before stated, the cord is brought to its initial clamped position. The circular button also serves to direct the cord to its position within the crotch 5 when said 10 cord is swung laterally, this cord when swung laterally to position under and back of the button, serving to wedge between the button and that portion of the cord on the package, thus completing or supplementing 15 the clamping action before mentioned.

A tie such as herein described can be cheaply manufactured and, by reason of its compact and durable construction will be found especially desirable for use in the handling of mail, and in packaging various 20 kinds of papers and the like.

What is claimed is:—

In a package tie, a flat finger piece having

an opening therein adjacent one end, a stem 25 projecting from and fixed relative to the other end of the finger piece and inclined relative thereto to form an obtuse angle, a circular button having a transversely rounded periphery, said button being fixedly mounted on said inclined portion and having one point on its periphery in the same 30 plane with the bottom face of the finger piece, said button being fixed on the stem and constituting package engaging means, and a cord secured at one end within the 35 opening in the finger piece and adapted, adjacent its other end, to engage the stem in the angle formed between the stem and the back face of the button.

In testimony that I claim the foregoing as 40 my own, I have hereto affixed my signature in the presence of two witnesses.

HAZEN ABBEY.
